UNITED STATES PATENT OFFICE.

BENJAMIN S. CHURCH, OF NEW YORK, N. Y.

EXPANSIBLE-FLUID TURBINE.

No. 878,118.

Specification of Letters Patent.

Patented Feb. 4, 1908.

Application filed October 5, 1904. Serial No. 227,294.

To all whom it may concern:

Be it known that I, BENJAMIN S. CHURCH, of the borough of Manhattan of the city, county, and State of New York, have invented certain new and useful Improvements in Expansible-Fluid Turbines, of which the following is a full, complete, and exact description, reference being had to the accompanying illustrations, which are hereby made part thereof.

The object of my invention is to produce a turbine, which can be designed within a large range of rotative speeds, being more particularly adapted to secure slow speeds of revolution, and also to produce a turbine which can be cheaply constructed because of the relatively small number and simplicity of its operative parts; possessing in addition the necessary requisites for obtaining a high degree of thermodynamic efficiency without undue size of the turbine as a whole.

Figure 1 is a side view of the turbine, having portions of the casing broken away to show the interior, the part R¹ shown in vertical section being a portion of the fixed guide port ring showing the ports passing through it, and the section being taken along the line 1—1 of Fig. 2. Fig. 2 is a sectional view taken on a plane perpendicular to Fig. 1 along the line 2—2.

The method of supporting the turbine is as follows: B is the base upon which the turbine rests and consists of a metallic support of any suitable design or shape and to which are bolted by the bolts b¹ b² b³ b⁴ the A-frame A¹ and two pillow blocks, one of which, P¹, is shown in Fig. 2 as supporting one end of the shaft S¹ upon which the A-frame A² rests in such a manner as to be permitted a slight angular movement around S¹. Each of the said A-frames is approximately Y shaped at its upper extremity, as shown in Fig. 1, and is provided with a pillow block P² on each arm of the Y, in which pillow blocks rest the trunnions t, t, indicated by dotted circles in Fig. 2, of the casing frames C¹, C², which are of approximately disk like shape with a lateral hollow projection or hub c¹, c², in the center thereof, and are provided with strengthening webs marked w, the lateral projections or hubs c¹, c², containing the journals in which the shaft S¹ revolves. These journals consist of cylindrical bushings D¹, D², shown in section in Fig. 2, each hav-

ing a spherical zone which fits accurately between the rings r¹, r², and the packing collars p¹, p², which are contained in the hubs c¹, c², and are retained in position by means of the bolts marked b². It will be readily apparent that by this arrangement, which is used as an example of one of the many equivalent forms of construction intended to fulfil the same end, any distortion of the turbine casing resulting from unequal pressures or temperatures upon its various portions can in no way result in any binding upon the shaft S¹, nor can it cause any strain upon the A-frames A¹ A².

In the spaces e¹, e², shown between the packing collars p¹, p², and the rings r¹, r², any suitable packing may be placed, if desired, for the purpose of preventing air from entering the vacuum within the casing where the turbine is operated condensing with steam as the expansible fluid; but no packing is shown because it is believed that with accurate workmanship the amount of air entering the casing would be insignificant, and in the absence of a condenser it is obvious that no packing of any kind would be needed.

The turbine proper is described as follows: The casing of the turbine consists of the two casing frames C¹, C², already described, two side castings E¹, E², and a center casting F. The side castings E¹, E², are fitted accurately to the casing frames C¹, C², and to the center casting F, and are bolted to them by suitable bolts marked b¹. The center casting F and the casing frames C¹, C², are divided into a number of chambers by means of the partitions marked x, as shown in Fig. 1, and the side castings E¹, E², are similarly provided with approximately radial partitions which register accurately with the partitions marked x, except as shown by the dotted lines in Fig. 1, which indicate partitions passing behind the ring partitions Z¹, Z², which ring partitions are shown in section in Fig. 2, and fit accurately upon the partitions marked X and the port-rings R¹, R², which they assist in retaining in position. It will accordingly be seen that the turbine casing is divided on each side into a series of chambers arranged approximately radially side by side and increasing in size from the upper part to the bottom of the casing. The passages, some of which are marked g in Fig. 1, extend through the center casting F between each

pair of the similarly located chambers for the purpose of equalizing any inequalities of pressure which might exist between the said pairs of chambers and are intended to prevent any inequalities of axial thrust resulting from such different pressures. The center casting F may be provided with the web f , as shown, which may, if desired, be extended so as to cut off the passages marked g , and in this manner the chambers on one side of the casing may be prevented from communicating with the similarly located chambers on the other side of the casing. Such a division would be necessary should the turbine be operated with one side only in a manner subsequently to be explained.

The guide port-rings R^1 , R^2 , of which R^1 is shown in vertical section in Fig. 1, for the purpose of showing the relative sizes of the ports passing through the said rings, are fitted accurately to and are supported by the casing frames C^1 , C^2 and the side castings E^1 , E^2 , as shown in Fig. 2, and each of the said guide port-rings R^1 , R^2 is provided with two series of ports running outward in a manner similar to the guide curves of a hydraulic turbine and increasing in size from the upper part to the bottom of the said guide port-ring, the respective ports in each series being marked y^1 , y^2 , y^3 , y^4 , y^5 , y^6 and y^7 , each of the said chambers into which the casing is divided being provided with a port. The ports increase in size from the top to the bottom of the casing, and this increase is calculated to correspond with the increasing volume of the expanding fluid, which flows at a uniform speed through every one of the said ports as will subsequently be explained. A complete series of ports has not been shown in Fig. 1 for the sake of simplicity, a portion of each series being concealed by the side casting E^1 ; it is to be understood, however, that the ports not shown increase gradually in size from the port y^4 to the port y^7 on the right side, and from the port y^5 to the port y^6 on the left side.

Upon the shaft S^1 is suitably secured the wheel-disk G^1 which is inclosed between the casing frames C^1 , C^2 and clears them by a small space. Upon the periphery G^2 of the said wheel-disk G^1 are suitably attached two rows of vanes or bucket blades marked V of any suitable shape, one row on each side. The blades V clear the guide port-rings R^1 , R^2 , on the inside, and the edges of the radial partitions X , by a small space. H is the inlet or supply passage for the expandable fluid, and J is the exhaust.

At Q is shown a ridge upon the hub of the wheel-disk G^1 , the object of which is to throw off any oil that may work inward along the shaft S^1 into the channel U , from which it may be removed and thereby prevented from mixing with the exhaust.

In the operation of the turbine the expan-

sible fluid enters at H and is divided at K into two equal portions, as shown in Fig. 2, one of which passes down on each side of the turbine. As both sides are in all respects similar, it is sufficient to describe one side only. The portion of expandable fluid passing down the side shown in Fig. 1 after leaving K passes downward through the side casting E^1 between the radial partitions shown by dotted lines and behind the ring partition Z^1 , shown in Fig. 2, which with the aforesaid radial partitions forms a conduit or chamber for transmitting the expandable fluid to the chamber L of the casing frame C^1 . This chamber L is provided with two ports marked y^1 , as shown in Fig. 2, which are of equal size and through each of which passes one-half of the expandable fluid reaching the chamber L , one fourth of the entire amount entering at H . As each of these ports is the beginning of an exactly similar series of ports and chambers, it will be sufficient to describe a single series of the entire four. Taking the series shown on the left side of Fig. 1, the jet of expandable fluid which passes through y^1 makes an impact upon the vanes V of the rotating wheel-disk G^1 and passes into the chamber M , from which it moves downward between the radial partitions of the side casting E^1 into the chamber N in a manner in all respects similar to the passage of the expandable fluid from K to L . From N the expandable fluid passes out through the port y^2 against the vanes V into the chamber O , and from O it passes downward and then upward through the port y^3 , and so on through the ports y^4 and y^5 , and finally through the ports y^6 and y^7 to the exhaust J . It will be readily apparent that the expandable fluid operates through the series of ports shown on the right side of Fig. 1 in an exactly similar manner, and the symmetrical position of the respective series of ports around the turbine tends to counter-balance any radial thrusts produced by the jets of expandable fluid upon the rotating wheel-disk G^1 . As the expandable fluid passes from each port through the vanes and into the succeeding chamber its velocity is greatly reduced, and its kinetic energy not absorbed by the vanes is transformed into potential energy of pressure. The velocity of the expandable fluid through the chambers is accordingly so low as to reduce any skin friction to a minimum, but I may, if I desire, reduce the cross-sectional area of the chambers to any degree not incompatible with satisfactory operation. There is accordingly a series of continued transformations of potential energy of pressure into kinetic energy, with a resultant loss of potential energy of pressure at each succeeding chamber, the amount of such loss being equivalent to the kinetic energy of each jet absorbed by the rotating wheel. This proc-

ess is carried on until the pressure is reduced to a minimum according to the conditions governing the expansion of the expansible fluid. As the amount of kinetic energy developed at each port depends upon the degree of expansion taking place, and that upon the size and proportion of the particular port to the series of ports to which it belongs, it is evident that by this method of constructing a turbine the best conditions for thermodynamic efficiency may be attained. It is generally desirable, but not essential, to have the amount of kinetic energy developed at each port, and consequently the velocities of the jets of expansible fluid, uniform, which, as stated above, is gained by a proper proportioning of the successive ports; but I may, if I desire, adopt a different method of proportioning the ports in cases where other considerations than the highest theoretical efficiency are of importance.

From the foregoing description it would appear that one side only of the turbine, as for instance that shown in Fig. 1, forms a complete turbine, but the reason for adding the other side, as shown in Fig. 2, is to prevent all axial thrust, which is thereby completely eliminated. In Fig. 2 I show a thrust block T which may be of any suitable form, as indicated, and is intended merely to prevent the wheel disk G¹ from moving sidewise and striking the sides of the turbine casing, should the bearings of the shaft S¹ not be strictly horizontal, or for any other reason extraneous to the internal operation of the turbine. I may also provide buffers or collars of any suitable form within or without the casing for the same purpose, which I have not shown for the sake of simplicity, as their proportions and location would readily suggest themselves.

While I have shown an outward flow radial turbine, I may if I so desire adapt my method of construction to any of the well known forms of turbines, as, for instance, to a parallel or axial flow turbine; and I may also dispense with one side of my turbine, should this construction under certain conditions be desirable, as in cases where the turbine is used in connection with a screw propeller, where the turbine may be constructed with two entirely separate and distinct sides, one producing a motion of rotation in the reverse direction to the other; in either direction the axial thrust being balanced against the thrust of the screw.

Having now fully illustrated and described my invention, what I desire particularly to claim is

1. A turbine for expansible fluids comprising a casing having a plurality of series of chambers for the expansible fluid, graduated ports in the said casing leading from one chamber into the next succeeding chamber

of the series, and a wheel having bucket blades interposed between each of the said ports and its succeeding chamber.

2. A turbine for expansible fluids comprising a casing having a plurality of series of chambers, each series having its chambers arranged radially side by side with graduated ports in the said casing leading from one chamber into the next succeeding chamber of the series, and a wheel having bucket blades interposed between each of the said ports and its succeeding chamber.

3. A turbine for expansible fluids comprising a wheel-disk having bucket blades arranged in circles concentric with its axis of rotation, and a casing provided with a plurality of series of chambers, each chamber having a graduated port or nozzle leading into the chamber next succeeding it, and each of the said series of chambers being situated adjoining one face of the wheel disk, a row of bucket blades being interposed between each of the ports and the next succeeding chamber of each of the said series of chambers.

4. A turbine for expansible fluids comprising a wheel disk provided with bucket blades and a casing having a plurality of chambers arranged in a plurality of series with a graduated port or nozzle leading from each chamber to the chamber next succeeding it, each series of chambers being situated adjoining one face of the wheel-disk and the said chambers and graduated ports increasing in size to correspond with the increasing volume of the expanding fluid.

5. A turbine for expansible fluids comprising a wheel-disk provided with bucket blades, and a casing having chambers arranged radially in series and communicating by means of ports proportioned to produce a predetermined fall of pressure, each of said series being situated adjoining the face of said wheel disk.

6. A turbine for expansible fluids comprising a wheel-disk provided with bucket blades, and a casing having an inlet for the expansible fluid and an exhaust arranged diametrically opposite thereto, and having chambers arranged in series and communicating by means of ports, each of said series of chambers communicating with the said inlet and the said exhaust, and being situated adjoining one face only of the said wheel disk.

7. A turbine for expansible fluids comprising a casing having a plurality of series of chambers, each series consisting of a succession of chambers containing the expansible fluid in decreasing stages of pressure, the said chambers being provided with a series of ports or nozzles so proportioned as to produce a predetermined fall of pressure from chamber to chamber; and a single row of blades coöperating with each of the said series of ports or nozzles.

8. A turbine for expansible fluids comprising a casing having a plurality of series of chambers or reservoirs, each series consisting of a succession of reservoirs, communicating successively by means of a corresponding series of ports or nozzles; and a wheel having rows of bucket blades coöperating with the

said ports or nozzles, each of said series of ports or nozzles coöperating with a single row of bucket blades.
